UNITED STATES PATENT OFFICE.

FRANK M. ASHLEY, OF NEW YORK, N. Y., ASSIGNOR OF ONE-HALF TO
ALBERT T. SCHARPS, OF NEW YORK, N. Y.

INKSTAND.

No. 830,633.

Specification of Letters Patent.

Patented Sept. 11, 1906.

Application filed August 10, 1904. Serial No. 220,162.

To all whom it may concern:

Be it known that I, FRANK M. ASHLEY, a citizen of the United States of America, and a resident of the city of New York, State of 5 New York, have invented certain new and useful Improvements in Inkstands, of which the following is a specification.

My invention relates to inkstands; and the object of my invention is to produce a stand 10 composed of permanent parts, neat design, minimum evaporation, easily filled and cleaned, large capacity, and in which the pen-holder is not liable to become soiled by reason of inserting it within the well or against 15 the sides of the dip-tube.

My invention consists in the novel form and the arrangement of the parts, which consist of but two at most.

Referring to the drawings which form part 20 of this specification, Figure 1 is a central vertical section of my improved inkstand, in which the dip-tube is held by the inturned rim of the well, and illustrates the proportions of the stand, which is one of its most important features when judged from the stand-point of utility. Fig. 2 shows another form 25 in which the dip-tube and cover is supported on an inclined surface or cone-shaped ring, for reasons hereinafter set forth. Fig. 3 is a plan view of Fig. 2, illustrating the design of the stand, which I prefer should consist of a square base with a round well therein and a dome-shaped top. This makes a stand of 30 very attractive appearance, which sits low on the desk, and is not easily overturned.

My design is such that it may be easily molded from glass, and when made from this material it is necessary to provide for the variation in shrinkage and form which glass is 40 subject to to insure the proper fit of the part holding the dip-tube to the base. This I have solved in a very simple and effective manner hereinafter explained. I wish also to note that the drawings as here shown are 45 practically working drawings so far as dimensions are concerned—that is, that the depth of the well is about as shown in all cases; but the diameter may be increased to any desired size.

Referring to the drawings, A indicates the base of the stand; B, the cover; C, the dip-tube, made integral with the cover; D, the well, and E the depression formed therein.

The base of the stand I prefer to make square, as shown, and the well D and side walls D' 55 are circular in form, the side walls D' being molded first in the form of a cylinder open at the top and then turned into the desired degree to hold the cover B, as shown in Fig. 1, or to prevent the spilling of the ink when the 60 base A is moved laterally, as shown in Fig. 2.

In Fig. 1 the cover B rests in the top of the stand at B', but is not a tight fit and is easily removable. A vent for air is provided at B', so that the stand may be filled without removing the cover, if desired. A barometer-stand may be made of it by making the cover 65 an air-tight fit with the base, and in this event the ink would usually stand low in the dip-tube, even though the main reservoir 70 was full. By making a series of air-vents all around the cover, as B', the resulting projections may be left thin enough, so they will crush more or less, and thus conform to the small differences in diameter where the 75 cover B fits. F is the penholder, G the pen, and G' the eye thereof. It will be seen that the depth of the well and its depression is less than the length of the pen and that the eye of the pen is on a line with the bottom of the 80 main reservoir of the well D. These dimensions are very essential to the utility of the stand, as they allow practically all of the ink to be taken up by the pen and yet prevent the penholder from becoming fouled by reason of touching the sides of the dip, which is the great objection to stands of this type 85 heretofore made.

In Fig. 2 the joint is made between the cover and base by forming a circular cone-shaped ring on the base A at H and making the cover B to fit the same. This prevents the glass from rattle and assures a joint, even though the glass may vary, as it does more or less. The large cover B is also of sufficient 90 weight to hold its position and is not easily knocked off of its base A. I indicates the coring in the bottom of the base A, which allows the glass to set quicker when molding and saves in weight and expense. The walls 100 of the dip-tube C project through the well or reservoir D into the depression E, and thereby the air-currents are prevented from entering onto the surface of the ink in the reservoir, and therefore the evaporation of ink is 105 prevented except on the small surface ex-

posed in the ink-dip C, and this condition obtains until the ink is all used up, which is not the case with other stands of this type.

While I prefer to make the stand of glass, it may be made of other materials without departing from the spirit of the invention.

The main reservoir and the depression are substantially of the same depth, so that the ink will reach the eye of the pen when the main reservoir is empty and yet not be so deep when the stand is full as to reach the end of the penholder.

Having thus described my invention, what I claim as new, and desire to secure by Letters Patent, is—

1. In an inkstand of the character described, a body having a main reservoir with a depression therein, said depression being of very small diameter compared to that of the main reservoir and the depth of the said reservoir and depression being substantially equal, a dip-tube resting loosely on the body and projecting into said reservoir to said depression, the combined depth of said reservoir and depression being approximately that of the length of a commercial pen; substantially as described.

2. In an inkstand of the character described, a body having a main reservoir with a depression therein, a dip-tube loosely resting on the top of the body and projecting into said reservoir to said depression, the diameter of the said depression being approximately that of the lower end of the dip-tube, the combined depth of said main reservoir and depression being approximately that of the length of a commercial pen; for the purpose set forth.

3. In an inkstand of the character described, a body having a reservoir with a de-

pression therein of comparatively small diameter to that of the said reservoir, a dip-tube supported from the top of the body and projecting into said reservoir to said depression, the combined depth of said reservoir and depression being approximately that of the length of a commercial pen; for the purpose set forth.

4. In an inkstand of the character described, a body having a square base with a dome-shaped top, a reservoir with a depression therein of comparatively small diameter to that of the said reservoir, a dip-tube supported from the top of the body and projecting into the said reservoir, the combined depth of said reservoir and depression being approximately that of the length of a commercial pen; for the purpose set forth.

5. In an inkstand of the character described, a body having a main reservoir with a depression therein, said depression being of very small diameter compared to that of the main reservoir, and the depth of the said reservoir and depression combined, being approximately that of the length of a commercial pen for the purpose set forth, the top of the stand being approximately a horizontal plane, a cover supported from the top of the stand and having a depression in its surface which extends within the reservoir to about the line formed by the under side of the top of the stand.

In testimony that I claim the foregoing as my invention I have signed my name, in presence of two witnesses, this 9th day of August, 1904.

FRANK M. ASHLEY.
